UNITED STATES PATENT OFFICE.

SILVIO PETRECCA, OF TOLEDO, OHIO.

CAN-CAPPING MACHINE.

Application filed April 3, 1926. Serial No. 99,650.

This invention relates to a can capping machine, the general object of the invention being to provide means for placing friction caps on cans, with means whereby 5 the device can be used with different sizes of cans.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation, with parts in 20 section, of the device.

Figure 2 is a view of the piston, with parts in section.

Figure 3 is a view of the split spring ring used with the piston.

In these views, 1 indicates the base of the device and 2 indicates the upright connected with the base and having a horizontal part 2' which is provided with the vertically arranged bore 3 which is of two diameters to receive the stem 4 of the piston 5 and the spring 6 which surrounds the upper part of the stem. An arm 7 extends upwardly from the upper part of the upright and has a tapered hole 8 therein which receives the tapered end of a handle 9 which has a hole therein to receive the upper end of the stem 4, the stem being pivotally arranged in the hole by means of the pin 10. The piston 5 is formed with the reduced lower part which is provided with the annular groove 11 in which fits a split spring ring 12. This reduced part enters the cap, shown at B, with the upper edge of the cap engaging the under face of the large part of the piston so that this part tends to force the edge against the top of the can. The spring ring 12 will engage the cap and hold it in place on the piston, and by making this ring of spring metal, it will act to hold caps of different

sizes on the piston so that the machine can 50 be used for capping cans of different sizes.

The can A to be capped is placed on the base 1 in front of the upright 2 and under the piston, the cap B having been placed on the piston, as shown in dotted lines in Figure 1. Then the handle is depressed, which forces the piston downwardly so that the cap is pushed into the can top and thus the can will be sealed. The spring will return the parts to raised position as soon as pressure 60 is removed from the handle. The spring ring will hold the cover squarely on the piston, so that it will not tilt when being forced into the mouth of the can. The device will insert the cap without injuring 65 either the can or the cap.

It is thought from the foregoing description that the advantages and novel features of my invention will be readily apparent.

I desire it to be understood that I may 70 make changes in the construction and in the combination and arrangement of the several parts, provided that such changes fall within the scope of the appended claims.

What I claim is:—

1. A can capping machine comprising a base, an upright thereon having a horizontal upper part which has a vertically arranged hole therein, a stem passing through the hole, a piston on the lower end of the stem 80 formed with a lower reduced part to receive a can cap, an upwardly extending arm on the upright having a tapered horizontal hole therein, a handle having a tapered end fitting in the hole for movably connecting 85 the handle with the arm, means for pivoting the handle to the stem and a spring on the stem between the handle and a part of the upright for holding the piston in raised position. 90

2. In a can capping machine, a piston or chuck having a reduced part for entering a can cap, said part having an annular groove therein and a split spring ring seated in the groove for causing the said piston or chuck 95 to fit can caps of different sizes.

In testimony whereof I affix my signature.
SILVIO PETRECCA.
